UNITED STATES PATENT OFFICE.

HERMAN B. THURSTON, OF CLEVELAND, OHIO, ASSIGNOR TO THE TALMAGE MANUFACTURING COMPANY, OF CLEVELAND, OHIO, A CORPORATION OF OHIO.

LOW-WATER ALARM.

Application filed July 18, 1924. Serial No. 726,710.

This invention relates to low water alarms for use in connection with steam boilers and constitutes an improvement over low water alarm devices, now in use. Particular reference is made to my prior application, Serial No. 701,598 filed March 24, 1924.

In this and a prior application, also of my own, namely Serial No. 643,512, filed June 5, 1923, are shown a conduit leading from the steam chamber of the boiler to a cage located near the crown sheet, and which contains a fusible element normally closing the conduit. A passage leading from this point communicates with an alarm device such as a whistle. Whenever the element becomes fused by the heat of the crown sheet, steam thus released travels along the passage and sounds the alarm. This occurs when the water in the boiler reaches a dangerously low level.

The present invention relates particularly to an improved means for supporting the fusible element and for providing communication between the conduit leading from the steam space and the outlet passage, which improvements present certain advantages as will hereinafter appear.

It is one of the primary objects of this invention to provide a fusible plug cage in which there will be less likelihood of the heat of the boiler fusing the plug prior to the water in the boiler reaching the danger level and which will by virtue of this construction respond quickly to the heat of the boiler when the danger level is reached. It is another object to provide a more open passageway for the melted metal of the fusible plug.

A further object is to provide an open plug cage whereby the easy cleaning and inspecting thereof and the removal of the fusible plug may be effected.

Another object is to provide a closure plug for the cage which is so secured within the cage that the threads are protected from steam on the one side and fire and resulting carbon deposits on the other. Another object is to provide for the removal of the plug from the cage without damage to the securing threads.

Other objects will become apparent in the further description of my invention relating to the accompanying drawings and the

essential characteristics thereof will be summarized in the claims.

In the drawings wherein I have illustrated the preferred form of my invention, Fig. 1 is a substantially central longitudinal cross-section through the water alarm; Fig. 2 is a transverse section through the communicating passageways in the cage as indicated by the line 2-2 in Fig. 1.

The invention is primarily concerned with the construction of the fusible plug cage which is shown as inserted from within the fire box into the crown sheet and in which ample angular internal surfaces provide for its ready insertion and removal. In the cylindrical chamber adjacent these surfaces the heat conducting and chamber sealing plug is provided with a flange below the securing threads fitted to form a convenient seal and which when the plug is being removed, scrapes off the accumulated cinders from the cylindrical walls of the cage. The length of the longitudinal openings leading from the fusible plug to the alarm conduit has been increased, and the surplus metal surrounding these passages, shown in my prior application, above referred to, has been removed substantially throughout their entire length. The construction of the fusible metal container has been simplified and extends below the wall into a large cavity formed in the closure plug.

In the drawings a short section of the crown sheet is shown at 1 and a similar portion of the roof sheet at 2. The space between these sheets has been considerably foreshortened for the purpose of more clearly illustrating my invention and it is to be assumed that a portion of this space is occupied normally by water, the level of which is of course always below the roof sheet. The conduit for the live steam which accumulates adjacent the roof sheet is provided with a stuffing box sleeve 10 shown as having an elbow 11 communicating by way of the pipe 12 and a combination union nut and elbow 13 with the downwardly extending central pipe 16.

The cage 17 which receives the lower end of the pipe at 18 comprises a substantially cylindrical lower portion 19 externally threaded at 20 for engaging the crown sheet and having an angularly formed socket 21.

for securing the sleeve within the crown sheet for removing it therefrom by a wrench. An adjacent cylindrical portion 22 rising therefrom is of slightly greater diameter 5 than that of the roots of the threads 24 which are engaged by threads on a closure plug 26.

Slightly above the threaded portion this chamber terminates in a heavy transverse 10 wall. The cylindrical exterior of the cage merges into a more compact section, having openings therethrough as shown in the cross section, Fig. 2. At the upper end the cage again assumes the cylindrical shape and is 15 shown as threaded at 30 complementary to the bell mouthed lower end of a tube 31.

The top of the cage is shown as having a cylindrical groove 32 into which the passages 28 extend. The central opening 36 in 20 the cage is threaded to receive the fusible plug 37. The fusible metal 39 normally fills a conical opening in the fusible plug 37 which narrows at the bottom and terminates in the aperture 40 in the head of the fusible 25 plug. The head which is preferably hexagonal in shape to facilitate removal, also has a through transverse opening 41 and it is shown as depending within the cup-shaped upper end of the closure plug 26. The rim 30 on the closure plug formed by this cavity seats against the transverse wall of the cage thereby forming an effective stop for the plug, which also increases the area of heat conducting contact surfaces.

35 The fusible metal 39 is coextensive with the threaded portion of the plug 37, that is to say it does not extend either above or below the position of the plug which contacts with the transverse wall 27, and it is thereby entirely subjected to the most direct conductivity of heat from the firebox through the plug 26 and the walls of the cage.

40 By virtue of the seal formed at this point and the annular flange 46, formed below the 45 threads on the plug, the threads are well protected against corrosion and abrasion when removing plug and may be formed with an adequate amount of root and apex clearance for facilitating the removal of the 50 plug. This construction affords the most effective conductivity between the closure plug and the upper wall of the cage. The size of the neck 47 connecting the upper threaded portion of the closure plug with the lower 55 angularly formed head 48 is determined by experiment so that the proper amount of heat may be conducted from the boiler to the fusible metal 39.

60 The dome sleeve 10 supports the outer conduit tube 31 and is provided with the usual packing gland 50 and nut 51. At the upper end of this tube, I provide an elbow 52 which has an enlarged central cavity 53 and a conical roof 54. The alarm which is 65 preferably a whistle such as shown at 55 is

threaded into this elbow at 56 and carries a member 57 having a receptacle facing the opening in the cavity 53 for trapping the fused metal.

It will be seen that I have provided a low 70 water alarm, the component parts of which are extremely simple to manufacture, which may be easily taken apart for inspection and quickly reassembled when desired. The replacement of the fusible element is easily 75 accomplished from within the firebox, it being only necessary to remove the plug 26 and the member 37. A very important advantage of this invention, it will be seen, is that 80 this replacement may be accomplished while the water remains in the boiler. Of course, as the removal of these plugs opens the steam passages, there must be no steam pressure in the boiler, but the amount of water in the boiler is immaterial and does not interfere with this replacement. Moreover by reason of the construction set forth, particularly with reference to the quatrefoil 85 cross section of the plug cage at the low water danger point and the contiguity of the 90 surrounding metal from the crown sheet, the device is made extremely sensitive and quick acting when the water in the boiler falls to a dangerously low level.

A specific advantage is that the hexagonal 95 head of the plug carrying the fusible metal allows convenient removal and replacement, while the cupped threaded head of the plug 26 provides for bypassing heat from the fire 100 box around the fusible plug head to the fusible metal, and assures open communication of the passages.

Having thus described my invention, I claim:

1. The combination in a low water alarm, 105 of a passage leading from the steam space to a signal member formed by adjacent tubes extending through the roof sheet, a cage to which the tubes are threaded, said cage being threaded into the crown sheet 110 and having a downwardly facing cavity and channels opening into the cavity and completing communication between the tubes, a removable plug in one of said channels adapted to normally interrupt said communication and having a passageway there-through and a fusible member normally closing said passageway, a closure member having a recess formed by a brim on said member a portion of the plug extending into 115 said recess, said closure member being threaded into said cavity and extending toward the fire box space and adapted to bypass heat from the fire box through the cage to the fusible plug.

2. In a low water alarm the combination 125 with a signal device, of tubular members forming a passage leading from the steam space to the device, a cage secured to the crown sheet of the fire box, said cage having 130

a cavity and longitudinal passages opening thereinto, one of which communicates with the tubular member leading from the steam space, another with the member leading to the signal, a closure for said cavity having a cupped inner end in intimate contact with the cage and a shank in spaced relation to the cage and extending into the fire box, a fusible metal plug in one of said passages

10 normally interrupting communication between one of said members and the cavity, said plug having a recessed head projecting within said cupped inner end of the closure, said closure serving to by-pass heat from the

15 fire space through the walls of the cage to the fusible metal.

3. In a low water alarm the combination of tubes leading from a steam space of the boiler to a signal, said tubes being connected

20 to a member threaded into an opening in the crown sheet and extending upwardly therefrom, having a downwardly facing cavity and having a wall through which a plurality of openings communicate with the tubes

25 and with said cavity, a plug for one of the tubes having a passage therethrough closed by a fusible material, said fusible material normally interrupting the passage of steam to the signal and said plug having a head

30 projecting into said cavity by which it may be removed and replaced, a closure for the cavity including a member having a shank extending downwardly toward the fire space and threaded into the cavity, and having an

35 upwardly facing recess separated from said head and surrounding it, the upper edges of the said member seating against said wall whereby to protect the threads on said member against corrosive effects of foreign matter entering the passages.

4. In combination in a low water alarm, of a passage leading from the steam space to a signal member formed of tubes extending through the roof sheet, a cage threaded

45 into the crown sheet into which the tubes are threaded having a downwardly facing cavity partially threaded and partially smooth and an opening completing communication between the tubes, a plug in one

50 of said openings adapted to normally interrupt said communication and having a fusible portion and means for removing said plug, a cupped closure member surrounding said means, threaded into said cavity and

55 extending toward the fire box space and adapted to by-pass heat from the fire box through the cage to the fusible plug, and a flange below the threaded portion of the cavity closely fitting the smooth portion,

60 whereby the threads are protected against scale.

5. In combination, a boiler having a crown sheet and a roof sheet, and a pair of tubes extending into the roof sheet, one communicating with the steam space and the

other with a steam operated signal, a member secured to the crown sheet and having a passageway affording communication between the inner ends of said tubes, a plug comprising fusible material normally closing said passageway, said member having a cavity opening into the fire space and a closure member for the cavity threaded into said cavity and arranged to by-pass heat from the fire space to said plug through the wall of said member, and means comprising an outwardly extending flange of greater diameter than the top of the threads on the closure member, closely fitting the cavity below the threaded portion, whereby the threads are protected against damage by foreign matter deposited in the cavity.

6. In a low water alarm for a boiler, in combination, a crown sheet and a roof sheet having an opening therein, a pair of tubes

85 extending through said opening, a cage secured to the crown sheet and rigid with said tubes, said cage having a cavity and passageways communicating with both tubes and said cavity, a plug containing fusible

90 material located within one of said passageways, closing communication between one of the tubes and said cavity and extending downwardly into the cavity, a closure member

95 threaded into the cage and having a recess surrounding the downwardly extending portion of the plug, said closure member seating against the roof of the cavity whereby to protect the threads of the closure member against corrosion, and said closure member having a portion thereof extending

100 into the fire space.

7. A low water alarm for a boiler having a roof sheet and a crown sheet, a pair of tubes extending through the roof sheet, one leading

105 to the steam space and the other to a signal device, a cage member secured to the crown sheet and rigid with the inner ends of said tubes, said cage having passageways communicating with both the tubes, one of said

110 passageways having a plug therein closing such communication to one of the tubes, said plug having a recess partially filled with fusible material, a passageway extending

115 transversely of said recess, a closure member threaded into the cage and in intimate contact therewith at its upper end along its top and side surfaces and having a pocket in its upper face into which the lower end of

120 said plug extends, said pocket being arranged to receive the fused material when the alarm is actuated, and said lateral passageways serving to direct steam through the plug from the tube normally closed thereby and into the passageways in the cage

125 leading to the other tube.

8. In a low water alarm for a boiler having a roof sheet and crown sheet, a pair of tubes extending through the roof sheet, one communicating with the steam space and the

- other with a signal, a cage member secured to the crown sheet and rigid with the inner ends of said tubes, a transverse wall in the cage having openings therethrough, one of 5 the openings communicating with one of the tubes and one communicating with the other tube, said latter opening being normally closed by a plug having a passage closed by fusible material, the cage member having a 10 cavity communicating with the said openings, and a closure member in intimate contact with the cage adjacent the roof of said cavity, the lower end of said closure member being separated from the cage in the 15 zone of engagement of the cage by the crown sheet whereby heat from the fire space is by-passed from the closure member through the cage to the fusible plug in a region well above the crown sheet.
- 20 9. A low water alarm for a boiler having a roof sheet and a crown sheet, a pair of tubes extending through the roof sheet one within the other, one of said tubes commu-

nicating with the steam space of the boiler and the other with a steam operated signal, 25 a member secured to the crown sheet of the boiler and having a cavity therein, a central passageway leading from the inner tube to said cavity and a series of vertical passageways communicating between the outer tube 30 and the cavity and disposed about said central passageway, a plug having fusible material forming a portion thereof normally closing said central passageway, said material being located in the zone of the vertical passageway, means for conducting heat from the fire space to the fusible material, the body of the cage having indentations between the passageways, whereby the heating effect of steam in the boiler augments the 35 40 heat conducted from the fire space to fuse said material when the water in the boiler falls below said passageways.

In testimony whereof, I hereunto affix my signature.

HERMAN B. THURSTON.
